UNITED STATES PATENT OFFICE.

SIMEON B. KIRTLEY, OF COLUMBIA, MISSOURI.

VISIBLE-ACCOUNT BOUND LEDGER.

1,276,229.

Specification of Letters Patent. Patented Aug. 20, 1918.

Application filed January 29, 1917. Serial No. 145,040.

To all whom it may concern:

Be it known that I, SIMEON B. KIRTLEY, a citizen of the United States, residing at the city of Columbia, county of Boone, and 5 State of Missouri, have invented a new and useful Visible-Account Bound Ledger, of which the following is a specification.

This invention relates to visible account bound ledgers.

- 10 An object of the invention is to provide a visible account bound ledger including series of sheets cut away in stepped relation to provide visible spaces having index characters thereon, in combination with series of 15 blank overflow sheets placed at intervals between the cut away sheets adapted to have entered thereon accounts which overflow or are carried over from certain of the cut away sheets.
- 20 Another object of the invention is to provide a visible account bound ledger including series of sheets cut away in stepped relation to provide visible spaces having master indexes permanently affixed thereon, and 25 having spaces adjacent to the master indexes adapted to have entered therein designations indicating the overflow sheets to which the accounts have been transferred that cannot be entered fully upon the master 30 index sheets, in combination with a series of overflow sheets placed at intervals for receiving the accounts aforesaid.

Another object of the invention is to provide a visible account bound ledger embodying the features above mentioned, and also 35 including a series of blank overflow sheets placed at or near the end of any subdivision of master index sheets.

Other objects will appear from the following description, in which reference is 40 made to the accompanying drawings illustrating the invention, in which—

Figure 1 is a view of the open ledger or book showing the master index sheets of one 45 series.

Fig. 2 is a view enlarged relative to Fig. 1 illustrating the indexes upon the master index sheets and the adjacent spaces for the reception of other characters, some of which 50 are shown in this view of the drawing.

Fig. 3 is a view similar to Fig. 2 in that it illustrates the number of the master in-

dexes and also illustrates one of the overflow sheets having an account entered thereon which has been transferred or carried 55 over from page 187 of the series of master index sheets.

Fig. 4 is a view illustrating the series of the overflow sheets placed at the end of the series of master index sheets.

The book or ledger 1 is divided into a series of divisions, a number of sheets being included in each division and one or more divisions of sheets being assigned to each letter of the alphabet. The number of divisions assigned to each letter varies in proportion to the frequency of its occurrence as the initial letter of names and in proportion to the number of pages in the book. Thus, letters which are of most frequent 70 occurrence as the initial letters of name have assigned to them a greater number of sheets than are assigned to the letters which are of infrequent or rare occurrence as the initial letters of names.

Each series of sheets thus provided is equipped with a manually engageable index tab 2 which, preferably, is attached to the first sheet of the series. In any instance in which two or more series of leaves are assigned to any particular letter an index tab is attached to one of the sheets of each series assigned to that letter. For instance, by reference to Fig. 1, it will be observed that two divisions of master index sheets are 80 assigned to the letter B and that there are two index tabs for the letter B, one of these index tabs being for each series of the master index sheets belonging to the letter B. So, also, the letter M is of frequent occurrence 85 as the initial letter of names and, for purposes of illustration, I have shown in Fig. 1 three series of sheets assigned to the letter M and have also shown three index tabs 2 for that letter, one of the index tabs being attached to a sheet of each series of sheets. Obviously, this arrangement may be varied and there may be any desired number of 90 series of sheets for any particular letter.

The upper marginal edges of the master 100 index sheets of each series are cut away in stepped relation as will be readily understood by reference to the drawings, in order to provide an exposed or visible space upon

each sheet of the series when the ledger or book is opened before any series of sheets. Adjacent to the upper edge of the exposed or visible space a designation of a page number 5 is permanently placed or affixed as will be readily understood by reference to the different views of the drawing.

Upon the visible space of each master index sheet thus constructed a series of identifying index characters are permanently affixed for identifying the names of the accounts which may be entered upon or opposite the respective pages. It is preferable that these index characters consist of the 10 initial letter of the surname of the account, and in some instances one or more of the letters following the initial letter of the surname. This will be clearly understood by reference to page 187 (Fig. 2) which illustrates the index characters or letters "For" 15 permanently affixed upon the visible space of the sheet followed by a space in which one or more other identifying or index characters may be entered by the user of the book 20 or ledger to designate and distinguish the account from others.

In the particular instance to which I am referring the letter *b* has been entered by the user of the book or ledger following the 25 letters "For," thus indicating or designating that the surname or identifying name of the account there indexed includes the syllable "Forb," thereby distinguishing that name from the preceding name indexed by the 30 syllable "Ford". In the case of the syllable "Ford" the letter "d" has been entered by the user of the book or ledger following the letters "For", and the letters "R. A." have been entered adjacent to the syllable "Ford" 35 thus designating that the name of the person so indexed includes the initial letters "R. A."

In the case of the account indexed by the syllable "Forb" the space for that account upon page 187, or upon the page opposite 40 page 187 as the case may be, has been filled and the account has been transferred or has overflowed so that it has been necessary to enter the continuation of that account upon another sheet.

45 In order to provide for such contingencies blank overflow sheets are placed at intervals between the master index sheets and, in case these blank overflow sheets extend to the upper marginal edge of the book or ledger, 50 they also are cut away in stepped relation to provide visible spaces thereon in which may be entered identifying characters to distinguish them from each other. For instance, in Fig. 3, an overflow sheet 3 is 55 shown before page 189, and this overflow sheet is cut away so that the succeeding master index sheets are visible to provide a space 4 adapted to have entered thereon an identifying character or index which, in the 60 present instance, is the page designation 65

189^a, thus distinguishing this page from the master index page 189.

The account which has been mentioned as including the syllable "Forb" indexed on master index page 187 (Fig. 2) has filled 70 or overflowed the space on or opposite master index page 187 in which a portion of the account was entered, thus necessitating that the remainder of the account be entered elsewhere. In order to designate the point 75 to which the remainder of the account has been transferred there is formed a space above and below the index characters on the exposed portions of the master index sheets in which may be entered identifying characters to indicate or point the places in the book or ledger to which the overflowing accounts have been transferred or carried forward. In the particular case being discussed the account indexed by the syllable 80 "Forb" has been transferred to the overflow sheet 3 preceding master index page 189 and designated 189^a, as mentioned. To indicate upon the master index sheet the fact that the account indexed by the syllable 85 "Forb" has been transferred to overflow sheet 189^a, the designation "189^a" is entered adjacent to the identifying or indexing syllable "Forb" upon the master index sheet 90 187, thus clearly designating that the account so indexed has been entered upon overflow sheet page 189^a. Turning to page 95 189^a, we find that the account of J. H. Forbis is the particular account which has overflowed or been carried over onto overflow sheet 189^a.

In Fig. 4 are illustrated a number of blank overflow sheets placed at the end of the series of master index sheets and cut away in stepped relation to provide visible spaces for 100 receiving identifying characters which are shown as consisting of pages 197^a, 197^b, etc.

Accounts may be carried or entered from page to page, or sheet to sheet, of the overflow sheets. In Fig. 2, on page 189, we find 105 that the account of Fox has been transferred or carried over from master index page 189 to overflow page 197^e, and turning to page 197^e illustrated in Fig. 4, we find entered thereon the account of J. D. Fox, and below 110 the designations 197^e on the overflow sheet is a space 5 in which a designation or index of the name Fox is entered by the user of the ledger or book. When the account of Fox has filled page 197^e this fact may be 115 visibly indicated upon the visible space 5 by a mark or designating character as shown at 6, thus indicating to the user of the book or ledger that the account of Fox is carried over to another overflow page or sheet 120 125 which, in the present instance, for purpose of illustration, is shown to be page 197^d, since the name "Fox" has been entered in the space 5 below the designation on the page on the visible portion of overflow page 197^d. 130

As previously suggested the indexes on the master index sheets also index and identify the names of the accounts which are entered on the pages opposite the respective 5 pages containing the master indexes. This will be understood by reference to Fig. 1 in which it will be observed that the account of "Farnsworth, S. H." is entered upon page 172, which is opposite page 173; and that 10 the master index on page 173 identifies or indexes this account.

The foregoing explanation in connection with the illustration of the features is deemed sufficient to enable any one familiar with 15 the devices of this art to understand that my invention consists in the provision of the overflow sheets placed at selected intervals in connection with the master index sheets constructed as described and embodying the 20 features mentioned and illustrated. I do not restrict myself to the use of this invention in a bound ledger or book, since it may be used with advantage in ledgers of the loose-leaf type; neither do I restrict myself to the 25 insertion of the overflow sheets at any particular places, nor to other unessential details.

What I claim and desire to secure by Letters Patent, is:—

30 1. A visible account bound ledger or book, comprising a series of master index sheets cut away in stepped relation to provide visible spaces, designations of the page numbers permanently affixed upon the visible spaces, 35 and master indexes also permanently affixed upon the visible spaces for identifying the accounts which may be entered on the pages, in combination with a series of overflow sheets between the master index sheets cut 40 away in stepped relation to provide visible spaces adjacent to the visible spaces and master indexes upon the master index sheets adapted to have entered therein page numbers governed by and relating to the page 45 numbers on the master index sheets.

2. A visible account bound ledger or book, comprising a series of master index sheets cut away in stepped relation to provide visible spaces, designations of the page numbers 50 permanently affixed upon the visible spaces, index characters permanently affixed upon the visible spaces and having spaces adjacent thereto adapted to receive designations of pages to which any indexed account 55 has been transferred, in combination with blank overflow sheets placed at selected intervals to receive the accounts overflowing or transferred from the master index sheets and provided with visible spaces adjacent to the visible spaces and index characters on the master index sheets adapted to receive 60 the designations of the page numbers which are entered adjacent to the index of the account upon the master index sheets, as afore- 65 said.

3. A visible account bound ledger or book, comprising series of sub-divisions of master index sheets in which each series is cut away in stepped relation to provide visible spaces upon the respective sheets, designations of 70 the page numbers permanently affixed upon the visible spaces, index characters for the accounts permanently affixed upon the visible spaces, and a number of blank overflow sheets at the end of each series of master 75 index sheets adapted to have entered therein accounts transferred or overflowing from the master index sheets.

4. A visible account bound ledger or book, comprising several sub-divisions of master 80 index sheets in which the sheets of each sub-division are cut away in stepped relation to provide visible spaces, designations of the page numbers upon said visible spaces, index characters permanently affixed upon said 85 visible spaces, spaces adjacent to said index characters adapted to receive the designations of the page numbers to which overflow accounts are transferred from any of the master index sheets, and a number of blank 90 overflow sheets at the end of selected sub- divisions having visible spaces adjacent to the visible spaces and index characters on the master index sheets adapted to have entered thereon designating page numbers 95 corresponding to the designating page numbers entered adjacent to the indexes on the master index sheets, as aforesaid.

5. A visible account bound ledger or book, comprising series of master index sheets cut 100 away in stepped relation to provide visible spaces, designations of the page numbers permanently affixed upon the visible spaces, master indexes permanently affixed upon the visible spaces adjacent to the page numbers, 105 a number of overflow sheets placed between the master index sheets and cut away in stepped relation to provide visible spaces adjacent to the visible spaces and designations of page numbers on the master index 110 sheets adapted to have entered therein page numbers governed by and relating to the page numbers upon the master index sheets, and also provided with distinguishing characters to distinguish the pages from each 115 other.

6. A visible account bound ledger or book, comprising series of master index sheets cut 120 away in stepped relation to provide visible spaces, designations of the page numbers permanently affixed upon the visible spaces, master indexes permanently affixed upon the visible spaces adjacent to the page numbers, 125 visible spaces adjacent to the master indexes adapted to have entered therein designations of the pages to which accounts are transferred from the master index sheets, series of overflow sheets between the master index sheets cut away in stepped relation to provide visible spaces adjacent to the visible 130

spaces and designations of page numbers on the master index sheets adapted to have entered thereon designations of the page numbers governed by and relating to the 5 master index pages and corresponding to the page numbers entered in said spaces adjacent to the master indexes as aforesaid, and

also provided with visible spaces for receiving identifying characters or indexes corresponding to the identifying characters or 10 indexes upon the master index sheets.

In witness whereof I have signed this specification.

SIMEON B. KIRTLEY.
